(74) Attorney, Agent, or Firm—Westman, Champlin & Kelly, P.A.

(57) **CLAIM**

The ornamental design for a liner for a paint container, as shown and described.

DESCRIPTION

FIG. 1 is an isometric view thereof;
 FIG. 2 is a side view thereof, as taken from the left side of FIG. 1;
 FIG. 3 is a side view thereof, as taken from the right side of FIG. 1;
 FIG. 4 is a front view thereof;
 FIG. 5 is a rear view thereof;
 FIG. 6 is a top view thereof; and,
 FIG. 7 is a bottom view thereof.
